(57) **CLAIM**

The ornamental design for a mobile phone, as shown and described.

DESCRIPTION

FIG. 1 is a front perspective view of a mobile phone showing our new design in which the display part has been unrolled; FIG. 2 is a front view thereof;

FIG. 3 is a rear view thereof;

FIG. 4 is a left side view thereof;

FIG. 5 is a right side view thereof;

FIG. 6 is a top plan view thereof where the bottom plan view is a mirror image;

FIG. 7 is a rear perspective view thereof;

FIG. 8 is a front perspective view thereof in which the display part has been rolled;

FIG. 9 is a front view of FIG. 8;

FIG. 10 is a rear view of FIG. 8; and,

FIG. 11 is a top plan view of FIG. 8 where the bottom plan view is a mirror image.

The broken lines shown in FIGS. 1, 2, 8 and 9 depict portions of the mobile phone that form no part of the claimed design.

1 Claim, 11 Drawing Sheets
